ANGLE SCRIBING APPARATUS

Leroy E. Ridgeway, Lomita, Calif.

Application August 3, 1936, Serial No. 93,985

8 Claims. (Cl. 33—21)

My invention relates to an apparatus for scribing angles on various shaped surfaces, particularly adapted for circular, curved, or polygon surfaces, and the objects of my invention are:

5 First, to provide an apparatus in combinative relation with a protractor for scribing angles on various surfaces;

Second, to provide an apparatus of this class which may be shifted on the surface and the 10 scribing continued on opposite sides of an object;

Third, to provide an apparatus of this class with double channel support so that it may be readily adapted to various surfaces in alignment with the longitudinal axis of the body;

15 Fourth, to provide an apparatus of this class in which the protractor is quickly and readily clamped in relation with its support to provide for scribing various angles;

Fifth, to provide an apparatus of this class 20 in which the protractor is supported by means of beveled surfaces relatively to its support to provide for accurate positioning of the protractor relative to its support;

Sixth, to provide an apparatus of this class 25 with a plurality of scribing arms in pivotal relation to each other to provide for scribing on a variety of surfaces in various positions;

Seventh, to provide an apparatus of this class 30 in which the scribing arms may be shifted to opposite sides of the body for scribing relatively large bodies on their entire periphery; and

Eighth, to provide an apparatus of this class 35 which is very simple and economical of construction, durable, efficient, easy to operate, and which will not readily deteriorate or get out of order.

With these and other objects in view as will appear hereinafter my invention consists of certain novel features of construction, combination, 40 and arrangement of parts and portions as will be hereinafter described in detail and particularly set forth in the appended claims, reference being had to the accompanying drawing and to the characters of reference thereon which 45 form a part of this application in which:

Figure 1 is a longitudinal sectional view of my angle scribing apparatus from the line 1—1 of Fig. 4 showing some of the parts and portions in elevation to facilitate the illustration; Fig. 2 50 is a transverse sectional view from the line 2—2 of Fig. 1; Fig. 3 is a plan view of the apparatus complete with the marking apparatus shown in straight folded relation and Fig. 4 is an end view of my angle scribing apparatus shown positioned 55 on a circular line and showing the marking

apparatus in position for marking the under portion on said circular line 7.

Similar characters of reference refer to similar parts and portions throughout the several views of the drawing:

5 The protractor member 1, protractor member supports 2 and 3, support pivot member 4, bolt 5, clamp screw 6, clamp screw lever 7, scribing arms 8, 9, and 10, spacer 11, marker support 12, and marker 13 constitute the principal parts 10 and portions of my angle scribing apparatus.

The protractor member 1 may be of conventional type and have the conventional invex degree markings thereon from the middle outwardly to 90° except that the protractor is less 15 than semi-circular so that the marker point is positioned in line with the 90° markings or center of the protractor. This protractor is provided on its upper side with a slightly less than semi-circular lug portion 1a which has its radial center in line with the marker 13 and a similar lug 1b on its lower side and the index portion is provided with a beveled groove 1c whose radial point is also in line with the marker point. This 20 protractor 1 is supported by means of this bevel portion 1c at its lower side on the support 3 which is provided with a conforming beveled lug portion 3a which fits in the beveled portion 1c as shown best in Fig. 1 of the drawing, thus 25 providing a definite fit between the member 3 and the protractor member and provide means for holding them in certain shiftable relation to each other. This member 3 is provided with two outwardly extending ledges 3b and 3c forming 30 a channel shaped lower surface adapting it to fit on curved or similar surfaces as shown best in Fig. 4 of the drawing.

Mounted on the upper surface of the index portion of said protractor 1 is the protractor member support 2, which fits on the flat upper surface and 40 is provided with extending ledges 2a and 2b similar to the ledges 3b and 3c but extending in the opposite direction so that their supports 2 and 3 may be reversed so that the ledges 2a and 2b fit on curved or similar surfaces if desired. The 45 upper side of the member 2 is provided with an opening 2c which provides means for viewing the protractor index at various shifted portions. The members 2 and 3 are pivoted on pivot member 4 which is provided with reduced ends adapted to 50 fit in similar openings in the sides of the members 2 and 3 and these members are supported by means of a bolt 5 passing through the body portion of the members 2 and 3 which provides slight hinge or pivotal movement of the members 2 55

and 3 at the protractor end. These members 2 and 3 are adapted to be clamped against the protractor by means of a clamp screw 6 which is provided with a head 6a on one end which fits in the body portion of the member 2 and the other end is screw-threaded in the body portion of the member 3.

Secured to the body of the screw 6 between the bodies of the members 2 and 3 is a hub 7a of a lever 7 which extends outwardly and provides means for turning the screw 6 for clamping the members 2 and 3 against the protractor member 1, the beveled portions of the protractor and the member 3 forming a definite fit for holding the protractor in certain relation when clamping for providing accurate angular position of the protractor.

Mounted centrally on the flat portion of the protractor member 1 by means of a screw 8a, which is provided with a countersunk head, is the one end of the scribing arm 8, the other end extending outwardly against the flat side of the protractor as shown best in Fig. 3 of the drawing, and pivotally connected with the extended end of this scribing arm 8 is another scribing arm 9 which is approximately one-half the length of the scribing arm 8, and pivotally connected with the free end of the scribing arm 9 is another scribing arm 10 which is spaced from said free end by means of a spacer 11, and secured on the free end of the scribing arm 10 is a marker support 12 which consists of a rectangular in cross section casing member 12a which fits over the free end of the arm 10 and is provided with an extended portion 12b which is secured to the outer side of the scribing arm 10. This casing is provided with a screw 12c which is adapted to clamp against the outer surface of the arm 10 so that when the marker 13 is positioned on the opposite side of the member 10 in the casing 12a it may be readily clamped by tightening the screw 12c. It will be noted that the inner side 13a of the marker 13 is the central line for the protractor when folded in a position shown in Fig. 3 of the drawing.

Though I have shown and described a particular construction, combination, and arrangement of parts and portions, I do not wish to be limited to this particular construction, combination, and arrangement, but desire to include in the scope of my invention, the construction, combination, and arrangement substantially as set forth in the appended claims.

Having thus described my invention, what I claim as new and desire to secure by Letters Patent is:

1. In an angle scribing apparatus, a pair of channel members with their leg members extending outwardly in opposite directions hinged together near their one end and means for clamping said members together at their opposite ends.

2. In an angle scribing apparatus, a pair of channel members with their leg members extending outwardly in opposite directions hinged together near their one end, means for clamping said members together at their opposite ends, and a protractor shiftably mounted between the clamping ends of said channel members.

3. In an angle scribing apparatus, a pair of channel members with their leg members extending outwardly in opposite directions hinged together near their one end, means for clamping said members together at their opposite ends, a protractor shiftably mounted between the clamping ends of said channel members, and a marker pivotally connected with said protractor at its radial center.

4. In an angle scribing apparatus, a pair of channel members with their leg members extending outwardly in opposite directions hinged together near their one end, means for clamping said members together at their opposite ends, a protractor shiftably mounted between the clamping ends of said channel members, a marker pivotally connected with said protractor at its radial center, and a plurality of pivotally connected arms for supporting said marker in relation with its pivotal connection.

5. In an angle scribing apparatus, a pair of channel members with their leg members extending outwardly in opposite directions hinged together near their one end, means for clamping said members together at their opposite ends, a protractor shiftably mounted between the clamping ends of said channel members, a marker pivotally connected with said protractor at its radial center, said protractor provided with a beveled circular groove engageable with a conforming raised portion on one of said supports.

6. In an angle scribing apparatus, a protractor support including a channel member, a protractor shiftable thereon with its center point in alignment with the longitudinal axis of said channel member, and said protractor and channel member fitted together by means of beveled surfaces to provide accuracy of position.

7. In an angle scribing apparatus, a pair of supports hinged together near their one end, means for clamping said members together at their opposite ends, and a protractor shiftably mounted between the clamping ends of said supports.

8. In an angle scribing apparatus, a pair of supports hinged together near their one end, means for clamping said members together at their opposite ends, a protractor shiftably mounted between the clamping ends of said supports, and a marker pivotally connected with said protractor at its radial center.
